UNITED STATES PATENT OFFICE.

JOHN W. NASMITH, OF MANCHESTER, ENGLAND.

COMBING MACHINE.

Application filed March 21, 1923. Serial No. 626,661.

To all whom it may concern:

Be it known that I, JOHN WILLIAM NASMITH, of Heaton-Mersey, Manchester, England, have invented certain new and useful

5 Improvements in Combing Machines, of which the following is a specification.

In my United States Patent No. 1,369,532 there is described and shown a combing machine with a top comb that can be removed bodily from the machine for cleaning and repairs and it is so arranged that it can not be drawn away until the needles of the comb have been raised up quite clear of the leather covered detaching rollers. But it 10 has been found that, although in removing the comb the needles could not easily touch the roller yet an inattentive operative in replacing the comb could, if careless, let the needles touch the roller to the detriment of both, and one object of the present invention is to provide means to prevent this. It has been further found to be unnecessary to remove the comb entirely from the machine merely to clean it and a further object is 15 therefore to provide a convenient rest for the comb to support it whilst the operative removes any fibres or seed which may get fixed in the comb. This rest and the above mentioned preventive means are conveniently combined but might if desired be separate. Reference to the appended drawing along with the description will make the 20 invention clear.

In the said drawings, Figure 1 shows the mechanism in vertical longitudinal section; Figure 2 is a similar view of the mechanism at one point during the removal of the comb; and Figure 3 shows part of the cradle which rocks the top comb.

25 The cradle T⁷ which rocks the top comb is pivoted freely on the shaft T⁸ and rocked to and fro by the oscillating shaft W through the connecting rod T⁶ and the swivel T⁹, hinging on the stud T⁸ fixed in the lower end of the cradle. The lower end of T⁷ is formed with a slot T¹⁰ and the forward member of the slot is prolonged as an arm T¹² terminating in a notch T¹³. The upper face of the arm is conveniently made as an 30 arc of a circle with center at T⁸. Fig. 3 shows the lower end of the cradle. The arm T¹², forming the forward side of the slot T¹⁰, is united to the leg of the cradle T⁷ by the bridge b Fig. 3 cast together with them. 35 The top comb arm T² also swings on the center T³ when in working position and is ad-

justable in the vertical direction by the set screw T⁵. In the lower end it carries a pin T¹⁴ which engages in the slot T¹⁰ and when the comb is in working position with the 40 screw T⁶ resting on the shaft T³ the stud T¹⁴ is in the lower end of the slot T¹⁰ as shown in Fig. 1. It is therefore obvious that, before the comb can be drawn forward the pin T¹⁴ must be lifted clear of the top of the 45 slot T¹⁰, when the needles of the comb T are quite clear of the roller d. But the tail T⁴ is not yet quite clear of the shaft T³ (Fig. 2) but rests against it whilst the pin T¹⁴ is drawn forward along the arm and into the 50 notch T¹³ where it rests suspended in a convenient position for clearing the needles, the needles travelling along the dotted path p to the dotted position shown in Fig. 1. On pushing the comb back out of the notch its 55 own weight suffices to cause it to slide back and drop automatically into its working position, the needles again following the path p until they are clear of the back of the roller d before it can drop to its place. 60

Obviously other means of guidance and support might be devised without departing from the spirit of the invention.

Claims:

1. In a combing machine a top comb 65 rocking on an independent center, means for rocking the said comb and means whereby the comb is guided well clear of the detaching rollers both when it is lifted and when it is drawn forward, the said latter means 70 being such as to prevent replacement of the comb in working position unless it be held well clear of the detaching rollers. 75

2. In a combing machine, a top comb resting on an independent centre, means for 80 rocking the said comb, means for lifting and drawing the comb forward clear of the detaching rollers, and a support on which the comb may rest when so drawn forward. 85

3. In a combing machine a top comb rocking on an independent centre, means for 90 rocking the said comb and means formed on the said rocking means to guide the comb well clear of the detaching rollers during 95 removal and replacement. 100

4. In a combing machine a top comb rocking on an independent center, means for 105 rocking the said comb, means formed on the rocking means to guide the comb well clear of the detaching rollers during removal and replacement and means formed on the said 110 guiding means to support the comb in a con-

venient position for cleaning and clear of the
detaching rollers.

5. In a combing machine a top comb
rocking on an independent center, means for
5 rocking the said comb, means for guiding
and supporting the comb in position for
cleaning, the said guiding and supporting

means being such that when the comb is re-
leased from the supporting means it falls au-
tomatically into working position.

10 In testimony whereof I have affixed my
signature.

J. W. NASMITH.
